UNITED STATES PATENT OFFICE.

GEORGE W. COPE AND WILLIAM L. BERTRAM, OF DETROIT, MICHIGAN, ASSIGNEES TO
HOWARD STOVE CO., OF BEAVER FALLS, PENNSYLVANIA.

DESIGN FOR A STOVE.

No. 39,969.

Specification for Design.

Patented May 4, 1909.

Application filed March 15, 1909. Serial No. 483,655. Term of patent 7 years.

To all whom it may concern:

Be it known that we, GEORGE W. COPE and WILLIAM L. BERTRAM, citizens of the United States, residing at Detroit, in the county of Wayne and State of Michigan, have invented a new, original, and ornamental Design for Stoves, of which the following is a specification.

Reference is had to the accompanying drawing, in which:—

The figure is a perspective view of a stove, showing our new and ornamental design.

What we claim is:—

The ornamental design for a stove, as shown.

GEORGE W. COPE.

WILLIAM L. BERTRAM.

Witnesses:

NELLIE KINSELLA,
A. J. BELKNAP.
